UNITED STATES PATENT OFFICE.

JAMES McGUIRE, OF BELLEVILLE, ILLINOIS, ASSIGNOR OF ONE-HALF TO
JOHN S. CARSON, OF BELLEVILLE, ILLINOIS.

GIG-SADDLETREE.

No. 805,314.

Specification of Letters Patent.

Patented Nov. 21, 1905.

Application filed September 9, 1901. Serial No. 74,838. (Model.)

To all whom it may concern:

Be it known that I, JAMES McGUIRE, a citizen of the United States, residing at and whose post-office address is Belleville, in the county 5 of St. Clair and State of Illinois, have invented new and useful Improvements in Gig-Saddletrees, of which the following is a specification.

My invention relates to gig - saddletrees; and its primary object is to provide a jointed 10 saddletree of simple, inexpensive, and durable construction made up of independent sections connected together detachably.

A further object of the invention is to provide a jointed sectional gig-saddletree so constructed as to present an extended exposed 15 metallic surface to the view, thus permitting of the elaborate ornamentation of a harness by gold or silver plating.

A further object is to provide a strong and 20 durable attachment of the checkrein - hook with the saddletree.

The construction of the improvement will be fully described hereinafter in connection 25 with the accompanying drawings, which form part of this specification, and the novel features will be pointed out and claimed.

In the drawings, Figure 1 is a view in perspective of a saddletree embodying my invention. Fig. 2 is a view of the central section 30 and on one of the side sections, the checkrein-hook, and securing devices, the respective parts being separated, but so relatively arranged as to indicate their positions when assembled. Fig. 3 is a top plan view of the 35 center and saddle-seat.

The saddletree comprises an exposed central section 1 and two side plates 2, the central section having the seat 3 cast integral therewith. Each end of the central section 40 is formed with a transverse slot 4, providing eyes into which engage upwardly-extending hooks 5, projecting from beneath the ends and formed integral with the upper ends of the side sections 2. I provide the upper 45 ends of the side sections 2 next the hook ends 5 with shoulders 5' and 5'', arranged in line one above the other, the ones 5' forming, in connection with the hooks 5, recesses 5'', wherein are movably mounted the cross-bars 4' of the central sections, whereby when the 50 hooks 5 engage the slots 4 of said central sections they serve to prevent the disengagement of the hooks and cross-bars from their respective engagements, which is accom-

plished by means of said shoulders 5'' having 55 a positive bearing on the upper surface of the saddle-pad. The upper surface of the seat 3 is formed with a longitudinal recess 6, extending from its front edge for a distance approximately half its length, within which 60 rests the lower arm 7 of the checkrein-hook. This hook has its upper arm 8 extended rearward to the rear edge of the saddle-seat and downwardly curved, as clearly shown in the drawings, to prevent accidental disconnection 65 therefrom of the checkrein. The hook is secured to the center of the saddletree by means of a threaded stem 9, extending through an opening 10 of the central section of the saddletree, and a nut 11, engaging said stem. As 70 the arm 7 of the hook fits within the recess 10 in the surface of the seat and is firmly held therein by the nut 11, a secure and reliable attachment of said hook is effected. The central section 1 is also formed with threaded 75 openings 12, located adjacent to the slots 4 to receive pad-screws 13, which engage the usual socket-plates and secure the central section upon the saddle-pad. The side sections are each formed with a ring or loop 14 80 for the attachment of the saddle-girth 15, as shown in Fig. 1. Each of the side sections is also formed with an opening 17 to receive a terret 18, having a threaded stem 19 and an opening 20 to receive a pad-screw 21. It 85 will be obvious that the jointing of the side sections enables them to adjust themselves to fit the back of the horse, and as the adjustable sections are designed to be manufactured in different sizes the saddle will be 90 adapted for all the requirements of use.

The invention is equally adapted for single pad or double harness. The hook connection of the side sections with the central section of the tree renders the latter movable and 95 self-adjustable without liability of accidental detachment, and the shoulders and hooks projecting outwardly from beneath the ends of the central section and through the slots, respectively, the sections cannot be separated 100 until the side sections are turned upwardly over the lower parts of the central section.

Another advantageous feature of the invention is that the sections of the tree are exposed so as to be visible above the pad, 105 thus presenting an extended metallic surface for plating and adding greatly to the ornamental appearance of a harness.

I claim—

A gig-saddletree comprising a central section having at its lower ends rectangular slots, a side section provided with an opening 5 at its lower end, a hook on the upper end of the side section, and shoulders contiguous with said hook, the shoulders being arranged one above the other, the upper one of which forms with the hook a recess in which is 10 detachably mounted the cross-bar of the slotted end of the central section, said hook being also detachably mounted in the slot

and said lower shoulder being contiguous with said hook and adapted to rest on the upper surface of the said saddle and serving 15 to prevent displacement of said bar and hook from their respective seats, substantially as specified.

In testimony whereof I affix my signature in presence of two witnesses.

JAMES McGUIRE.
